Patented Oct. 29, 1918.

Sam G. Gillespie, Inventor
Frank D. Allen, Attorney

UNITED STATES PATENT OFFICE.

SAMUEL G. GILLESPIE, OF CHARLESTON, WEST VIRGINIA.

WATER-BASIN STOPPLE.

1,283,149.

Specification of Letters Patent. Patented Oct. 29, 1918.

Application filed August 6, 1918. Serial No. 248,541.

To all whom it may concern:

Be it known that SAMUEL G. GILLESPIE, a citizen of the United States, residing at Charleston, in the county of Kanawha and 5 State of West Virginia, has invented certain new and useful Improvements in Water-Basin Stopples, of which the following is a specification.

My invention relates to a stopple particularly applicable to the outlets or drains 10 of plumbing fixtures such as wash basins.

One general aim is to provide the stopple of metal so as to be free from interstices like rubber, especially after continued use 15 which clog with foreign matter and become unsanitary, and so as to be at all times capable of cleaning for sanitation.

Another object is to provide the specific construction hereinafter described, especially having novel manipulation and fastening means.

In the accompanying drawings illustrating the present preferred embodiment;

Figure 1 is a vertical section through the 25 improvements and an outlet member with which it is associated; Fig. 2 is a side elevation at a right angle to Fig. 1 of the improved device; Fig. 3 is a bottom view of the parts of Fig. 1; and Fig. 4 is a cross-sectional view on the line 4— of Fig. 2.

Referring specifically to the drawings, a water outlet pipe member of usual form for stationary basins is shown at A having a flange B to overlap the basin, an inlet C for 35 overflow water and a cross guard or trap bars D. Disclosure of this part will facilitate an understanding of the improvements.

The improvements constitute two parts, namely a stopple E and a fastening F therefor. Said stopple E is of suitable metal, 40 having a disk 5, preferably thin, to rest on the flange B and form a water seal therewith, and an annular wall 6 integral with or separate from the disk as desired and depending therefrom.

Fastening F is preferably made in a single strand of flexible metallic wire intermediate its ends being formed into a finger or manipulating loop 7, and into side arms 50 8 which extend through and are soldered or otherwise fastened to the disk 5.

Side arms 8 are elongated to permit free

vertical movement of the device and also extend below and on opposite sides of each of the bars D terminating in lugs 9, preferably in continuous relation, extending in opposite directions and underlapping the bars D. At 10, the side arms are preferably inclined upwardly and outwardly from lugs 9.

In attaching the improvement to the fixture, a finger of the operator or a tool may be interposed between the arms 8 to spread them so they will slip past the bars D, whereupon the arms 8 will spring inwardly to the normal position shown in the drawings, so that lugs 9 will underlap bars D. To remove the device the action is the reverse. In both attaching and removing the article inclined positions 10 will be found advantageous as the finger or tool by movement between the arms toward the lugs 9 will wedge or spread the arms 8 so that the lugs may be moved past the bars D.

As merely one embodiment has been 75 shown, it is understood that I may make such changes as fall within the spirit and scope thereof.

I claim:

1. A device of the class described having 80 a stopple, a fastening device of a single strand of flexible material passing through the stopple at two locations, to thus form a loop on one side and side arms on the other side, and means extending from the arms to engage and prevent detachment from a fixture.

2. A device of the class described having 85 a stopple, a wire bent intermediate the ends having arms passing therethrough and fastened thereto and having a manipulating loop on one side, said arms extending below the other face and having portions extending inwardly and downwardly to facilitate spreading of the arms, and lugs at the ends 90 of the arms extending in opposite directions.

In testimony whereof I affix my signature in the presence of two witnesses.

SAMUEL G. GILLESPIE.

Witnesses:

J. C. GRYMES,

WILLIAM GRANT.
